His Attorney.

UNITED STATES PATENT OFFICE

MARTIN McDONALD, OF WASHINGTON, DISTRICT OF COLUMBIA

DOORKNOB ATTACHMENT

Application filed May 14, 1929. Serial No. 362,928.

This invention relates to door knob attachments, and has for its object to provide a new and improved device for concealing and preventing looseness and loss of the screw 5 commonly employed for securing a door knob shank to the lock spindle.

The device of the present invention is complete in itself and includes two longitudinal sections or members capable of being conveniently assembled around the knob shank and secured to the door. The structure is such that the sections may be readily separated and removed in order to give access to the screw whenever it may become necessary 15 to remove the door knob.

With these and other objects in view, the present invention consists in the combination and arrangement of parts as will be herein-after more fully described, illustrated in the 20 accompanying drawings and particularly pointed out in the appended claims, it of course being understood that changes in the form, proportion, size and minor details may be made, within the scope of the claims, without departing from the spirit or sacrificing any of the advantages of the invention.

In the drawings:

Figure 1 is a vertical longitudinal sectional view taken through the door and a knob spindle and shows the device of the present invention in its operative position.

Figure 2 is a cross-sectional view on the line 2—2 of Figure 1.

Figure 3 is a perspective view of the attachment of the present invention, the longitudinal sections or members thereof being separated.

Figure 4 is a fragmentary sectional view illustrating the innerlocking of the inner 40 ends of the members of the device.

In Figure 1 of the drawings, there has been shown a door 1 through which extends the usual lock spindle 2 carrying the knob 3, which is provided with the usual cylindrical knob shank 4 having a rectangular bore, best shown in Figure 2 of the drawings, to snugly receive the rectangular spindle 2, whereby the spindle may be turned by the manipulation of the knob. As usual the 50 spindle is provided with a series of screw-

threaded openings 5 to receive the shank of the screw 6, which passes through the opening in the knob shank 4. These parts are common and well known and form no part of the present invention, but are shown in 55 the drawings in order to properly disclose the operation of the present invention.

Referring now more particularly to Figure 3 of the drawings, it will be seen that the present device includes upper and lower 60 longitudinal sections 7 and 8, which sections are semi-tubular in shape and are of the size to register and produce a cylindrical casing. At the inner ends of the members, there are provided the heads or flanges 9 and 10, which 65 may be semi-circular in shape or of any other desired configuration. The inner edges of the heads 9 and 10 are straight and rabbeted at 11 to form an interconnection for the members and prevent endwise looseness thereof. 70 The lower member 8 is provided at its outer end with a ring or band 12 integral therewith or secured thereto in any manner and arching over the open top of the lower section 8. 75

In using the device, the lower section 8 is placed upon the spindle, and then the knob and its shank are placed endwise upon the spindle and through the keeper 12, after which the lower section 8 is secured to the 80 door by means of a screw 13 passed through the perforation 14 in the head or flange 10. In this condition, the top of the knob shank 4 is in plain view so that it may be determined whether or not there is any space between the end of the shank 4 and the door and if such a space exists, the knob is removed, a washer 15 slipped over the spindle and then the knob replaced, after which the screw 6 is applied so as to hold the knob on 85 the spindle. Then the upper section 7 is ap- piled by inserting its outer end within the keeper 12 and then bringing it down into seating engagement with the top edge of the lower member 8, after which suitable fasten- 90 ings 16 are inserted through the openings 17 in the head 9 so as to hold the upper section 7 in place.

When all of the members have thus been 100 assembled, the upper section 7 entirely con-

ceals the head of the screw 6, is in contact therewith or in very close proximity thereto, and thereby prevents looseness and loss of the screw, whereby the knob will always remain 5 tight upon the spindle 2.

In order to remove the knob, the fastenings 16 are removed, after which the top section 7 may be tilted upwardly and its outer end withdrawn from the keeper 12, whereupon 10 access may be had to the screw 6 to release the knob.

From the foregoing description, it will be readily understood that the device of the present invention is entirely complete in 15 itself and capable of being applied to any ordinary door knob without requiring any change or alteration therein whatsoever and without requiring any change or preparation in the door. Aside from the three screw- 20 threaded fastenings, the device includes two members only, which may be cast or otherwise made in a very simple and inexpensive manner. When in place, the attachment effectually conceals and holds in place the 25 screw employed to secure the knob to the spindle, and when in place gives a neat and ornamental appearance.

What is claimed is:

1. The combination with a door knob and 30 its tubular shank, a lock spindle, and a screw extending through the shank and engaging the spindle to hold the knob thereon, of means for concealing and preventing looseness and loss of the screw, comprising a longitudinally split sleeve embracing the shank and covering the head of the screw, that end of the sleeve opposite the knob having an outstanding peripheral flange for connection with the door, and one of the sleeve members 40 being provided with a keeper located next to the knob and embracing the corresponding end of the other sleeve member.

2. A door knob attachment comprising a longitudinally split sleeve, one of the sleeve 45 members being provided with a keeper arching across its open side, the other sleeve member having one end embraced by the keeper, and the other ends of the members having outstanding heads or flanges provided with 50 openings for the reception of fastening devices.

3. A door knob attachment comprising a longitudinally split sleeve, one of the sleeve members being provided with a keeper arching across its open side, the other sleeve member having one end embraced by the keeper, and the other ends of the members having 55 outstanding heads or flanges provided with openings for the reception of fastening devices the meeting edges of the heads or flanges 60 being rabbeted.

MARTIN McDONALD.
